Attorney.

UNITED STATES PATENT OFFICE

1,984,398

PORTABLE ELECTRICAL APPARATUS

Charles Vance Dame, Lanark, Ill.

Application October 21, 1933, Serial No. 694,581

3 Claims. (Cl. 240—59)

This invention relates to improvements in portable electric apparatus.

In my co-pending application, Serial No. 533,854, filed April 29, 1931, now Patent No. 1,935,790 for Portable electric apparatus, of which application the present application is a continuation in part, I have disclosed an apparatus for carrying batteries or dry-cells about the waist of the wearer which provide current for a lamp or other device, which is detachably supported by a shoulder sling which assists in supporting the dry-cells.

One object of the present improvements is to provide an improved carrying mechanism for the lamp or other electrically energized device which, in case a lamp is employed, will enable the wearer to adjust the lamp universally to throw the light in the desired direction and will permit the ready removal of the lamp from the carrier for use as a hand lamp.

An additional object of the invention is to provide a sling which, in addition to providing an adjustable support for the lamp also forms a sheath or container for the flexible conductor connecting the lamp with the batteries whereby when the lamp is being carried in its normal position in the sling, the surplus conductor is concealed and out of the way.

Another object of the invention is to provide circuit establishing means for readily connecting fresh batteries in the lamp circuit, or the circuit of other current consuming apparatus which may be employed in lieu of a lamp when desired.

Other objects of the invention relate to various features of construction and arrangement of parts which will be apparent from a consideration of the following specification and accompanying drawing, wherein:

Figure 1 is an elevation of apparatus embodying the present improvements.

Figure 2 is a broken vertical sectional view through a dry-cell container and its associated circuit establishing device.

Figure 3 is a sectional view taken on line 3—3 of Figure 2.

Figure 4 is a vertical section through the lamp carrier section of the sling.

Figure 5 is a broken elevation of a preferred form of buckle for detachably securing the sling sections together.

Figure 6 is a sectional detail view of one of the spring buckle members.

Figure 7 is a plan view illustrating the preferred means for attaching the sling to the bat-

tery container and showing the lamp and cable pocket in section on line 7—7 of Figure 1.

In the drawing the battery or dry-cell container, indicated generally by the number 10, preferably is of the type shown and described in my above mentioned application.

The container comprises compartments 11 for dry-cells which are hinged together and attached to a belt 12 which encircles the wearer's body. The compartments have detachable cover plates 13 held in position by the longitudinal bolts 14 having nuts 15 at their upper ends.

Each plate is provided with a T-shaped member 16 which forms a casing for circuit connecting or establishing means for connecting the various dry-cells in the desired circuit. Secured to the lower side of the plates 13 are insulators 17 which carry resilient conductors 18 which are arranged to make contact with the terminals 19 of the dry-cells 20. Conductors 21 extend from the members 16 upwardly through the hollow members 16 and terminate in plug-in receptacles or sockets 22 which are supported by the insulating discs 23. Additional sockets 24 are likewise carried by the discs and each pair is connected by a conductor 25. For the purpose of electrically connecting the dry-cells together, conductors 26, 26 are provided, each pair of which has connector plugs 27, 27 which cooperate with the sockets or receptacles 22.

In Figure 2 the left hand end of the member 16 is provided with a special plug 28 having a conductor 28a therein which electrically connects the adjacent sockets 22 and 24.

The right hand plug 27 of the right hand member 16 as shown in Figures 1 and 2, is connected to a flexible conductor 29 which passes through a recess 30 in the sling section 31. This section is preferably made of flexible material and has an outer sheath 32 stitched or otherwise secured along its edges to the member 31, to form a pocket 33 in which is secured a metal tube 34 as shown in Figure 4. The tube 34 may be secured in position by cementing the same or by means of rivets such as are shown at 35. The forward portion of the upper edge of the tube may be spun or crimped over the upper edge of the sheath 32 as shown at 36 to facilitate placing the lamp handle 37 therein.

The handle 37 is preferably cylindrical in form and frictionally fits within the tube 34 and has an upwardly projecting neck 38 to which the lamp 39 is pivotally attached as at 40 to provide for the vertical adjustment of the lamp. The lamp may be swung on a vertical axis to the

position desired while in use due to the frictional engagement of the tube 34 with the cylindrical handle 37. It may also be raised and lowered within the limits of the tube as will be apparent.

5 A switch 40a for controlling the flow of current to the lamp may be provided at any convenient point but is shown as being located on the stem or neck 38.

The cable 29 is of such length that the lamp 10 may be withdrawn vertically from the tube 34 and used as a hand lamp. When the lamp is replaced, however, the surplus cable is carried in the pocket 33 of the sheath 32 and thus is out of the way.

15 The section 31 of the sling is attached to one of the containers 11 preferably by means of a catch 41 having open loops 42 which are adapted to be inserted beneath two of the nuts 15, of one of the battery containers.

20 The upper end of the sling section 31 preferably carries a catch or hasp 43, preferably formed of resilient or spring metal, and provided with open hooks 43a as shown for engaging spring pressed buttons 44a secured to the sling section

25 44. Member 43 is similar in construction to member 41 and as shown in Figure 6, its open loops may be readily moved into engagement with or disengaged from the spring pressed members 45 of the buttons 44a.

30 The opposite end of the sling section 44 is also provided with a member 41 which has its open loops secured beneath any convenient pair of nuts 15.

35 It is preferred to have the members 41 readily detachable as by loosening the nuts 15, so that the ends of the sling can be attached to any other pair of bolts to balance the weight of the battery carrier upon the sling to suit the comfort of the individual user.

40 With the present improvements fresh batteries can be installed readily first by disconnecting the plates 13 by removing the nuts 15 from the bolts 14, and then replacing the plates. Since the plates carry the contact arms 18 the circuit 45 of the lamp will be re-established properly as will be seen.

45 In the use of the apparatus, the battery carrier 10 is preferably carried on the wearer's side, whereby the sling will pass across his chest where 50 the lamp 39 is in position for directing the light generally in a forward direction. As the user moves the light moves with him, thus always illuminating his path of travel.

For special work the lamp may be adjusted on a vertical axis to cast the light to one side, or it may be adjusted on a horizontal axis upon the pivot 40 to cast the light at the desired angle to the horizontal.

5 The present apparatus is found convenient for use by farmers, miners, and others, and while the invention has been described and illustrated in conjunction with a lamp, it will be apparent that other electricity consuming devices may be 10 used with the apparatus in lieu of a lamp. I therefore do not wish to be restricted specifically to the modification of the improvements shown and described except as so limited by the appended claims.

15 I claim:

1. A portable electric device comprising a shoulder sling and a belt adapted to be placed around the wearer's body, a plurality of dry-cell compartments supported thereby, a cover section for each compartment having dry-cell contact members in the lower side thereof and plug-in receptacles on the upper side, conductors having connecting plugs for said receptacles for connecting said dry cells in circuit with a 20 current energized device, and a carrier on said sling for removably supporting said device.

2. A portable electric device comprising a plurality of flexibly connected battery containers provided with a belt and a shoulder sling for 30 attaching the same to the body of the user, said containers having covers removably bolted thereto, said sling having a carrier for an electrically energized device supplied with current by batteries in said container, and means for securing 35 the ends of said sling to any of said cover bolts.

3. A portable electric device comprising a battery container provided with a belt for attaching the same to the body of the user, a shoulder sling attached to said belt, a holder for an electric lamp carried by the forward portion of said sling, and a conductor for supplying current from the battery to the lamp, said lamp comprising a pivotally connected handle and lamp casing whereby the latter can be adjusted angularly with respect to the former, said handle and holder being arranged to provide for adjustment of the handle longitudinally and on a longitudinal axis, said casing being off-set forwardly from the axis of said handle whereby the lamp 40 can be swung arcuately about the longitudinal axis of the handle through a substantial arc.

45 CHARLES VANCE DAME.
